(57) **CLAIM**

The ornamental design for a harmonic actuator, as shown and described.

DESCRIPTION

1. Harmonic actuator

1.1 : Perspective

1.2 : Perspective

1.3 : Front

1.4 : Back

1.5 : Left

1.6 : Right

1.7 : Top

1.8 : Bottom

A harmonic actuator is used in many fields such as bionic robots, industrial robots, conveying robots, etc.; The broken lines in the drawings depict portions of the actuator for the caster that form no part of the claimed design.
